[57] **CLAIM**

The ornamental design for a facade panel arrangement for a disk drive chassis, as shown and described.

DESCRIPTION

FIG. 1 is a top perspective of the facade panel arrangement for a disk drive chassis, showing the new design;

FIG. 2 is a front view thereof on an enlarged scale;

FIG. 3 is a rear view thereof;

FIG. 4 is a bottom plan view thereof;

FIG. 5 is a top plan view thereof;

FIG. 6 is a right side view thereof; and,

FIG. 7 is a left side view thereof.

The broken line showing of a disk drive chassis in FIGS. 1-7 is illustrative of environmental structure only and forms no part of the claimed design, and the unclaimed chassis is shown broken to indicate an indeterminate width in FIGS. 2, 3, 6 and 7.
